UNITED STATES PATENT OFFICE.

TRUMAN G. PALMER, OF CHICAGO, ILLINOIS.

GAS-HEATER.

1,195,260.

Specification of Letters Patent. Patented Aug. 22, 1916.

Application filed December 20, 1915. Serial No. 67,791.

To all whom it may concern:

Be it known that I, TRUMAN G. PALMER, a citizen of the United States, residing at Chicago, county of Cook, and State of Illinois, have invented certain new and useful Improvements in Gas-Heaters; and I do hereby declare the following to be a full, clear, and exact description of the invention, such as will enable others skilled in the art to which it appertains to make and use the same.

This invention relates to gas heaters and has for its object to provide an improved heater which may either be supported upon a flat horizontal-surface, such as a floor or a table, or supported from a vertical surface, such as a wall. For this purpose, the base of the heater may be used as a wall bracket as well as a pedestal for use on floors, tables, etc., and is so designed that when used in either relation, it supports the heater in an upright position. This is accomplished by providing the base with a three-way connection, one of whose parts is adapted to be connected with a gas conduit, the other two parts being used to removably support the heater in the two positions of the base, that is, when the base is used upon a horizontal surface, one of such parts of the three-way connection is utilized to support the heater in an upright position, and when the base is supported from a vertical surface, the other of such parts of the three-way connection is utilized for supporting the heater in an upright position. The passage in that part of the three-way connection not being utilized for supporting the heater is closed to cause the gas to flow from the gas conduit through that part of the three-way connection upon which the heater is supported.

The invention is illustrated in the accompanying drawings, in which—

Figure 1 is a front elevation of the improved heater and its base illustrating the manner of connecting the heater to the base when the latter is supported upon a horizontal surface; Fig. 2 is a side elevation, partly in section, illustrating the manner of connecting the heater to the base when the latter is supported from a vertical surface, such as a wall; Fig. 3 is a side elevation, partly in section, of the base with the heater removed illustrating the manner in which the base may be supported from the wall; Fig. 4 is a bottom plan view of the

base; and Fig. 5 is a detail perspective view of one form of bracket which may be employed for supporting the base from the wall.

The heater shown in the drawings is of the same general type as that disclosed in my prior Patent, No. 1,125,387, of January 19, 1915, and need not be described in detail, as the specific construction of the heater is immaterial, so far as the present invention is concerned. For the present purpose, it is sufficient to note that the heater comprises a burner *a* which may be of the usual Bunsen type, and a gallery *b* associated with the burner. The gallery *b* supports a cylindrical foraminous heating shell *c* co-axially disposed in which is a baffle *d*. The flame from the burner heats the baffle and the foraminous shell and the heat thereof is reflected into the compartment to be heated by means of a reflector *e*.

The base of the heater is shown at 1 and when used either as a wall bracket, as exemplified in Fig. 2, or as an ordinary pedestal, as exemplified in Fig. 1, is capable of supporting the heater in an upright position. As above stated, this is accomplished by providing the base with a three-way connection. This connection is denoted generally by the reference character 2 and may be connected with the base proper 1 in any suitable manner, such as by means of the bolt 3. The three-way connection 2 comprises two parts 4 and 5 which are radially and horizontally disposed when the base 1 is supported in its horizontal position shown in Fig. 1, and a third part 6 which is vertically disposed when the base is supported in its horizontal position. The part 5 serves as a means of connection for the gas conduit 7 which serves to supply the gas to the interior of the three-way connection. It will be understood that the three-way connection has interior passages so connected that the gas may be supplied from the conduit 7 to either of the passages in the parts 4 and 6 of the three-way connection.

As best shown in Fig. 3, the parts 4 and 6 of the three-way connection are externally threaded and each is adapted to receive the lower portion of the burner *a*. When the base 1 is supported in its horizontal position, the lower portion of the heater is screwed upon the part 6 of the three-way connection and the part 4 is then closed by means of a cap 8. Under these conditions,

the gas will be supplied from the conduit 7 through the vertical branch 6 of the three-way connection to the heater and the heater will be supported in an upright position, as 5 shown in Fig. 1. The escape of gas to the atmosphere through the horizontally-extending portion 4 of the three-way connection is prevented by the closure cap 8.

As above stated, the base is adapted to be 10 supported from a vertical surface and to render this possible, the under portion of the base is recessed diametrically, as shown at 9, to accommodate a sheet-metal clip 10. As shown in Figs. 3 and 4, this clip is re- 15 tained in the recess by means of the bolt 3, and has an extremital portion which is bent back upon itself, as denoted at 11. This bent-back portion is adapted to be received by a bracket secured to the wall. Such a 20 bracket is shown in Fig. 5 at 12 and may be provided with a plurality of holes 13 by means of which the bracket may be secured to the wall by means of the nails or screws 14 (Fig. 3).

25 As shown in Fig. 5, the bracket 12 is provided with two struck-up portions 15 to form a socket for receiving the extremital portion 11 of the clip 10. When the bracket 12 is secured to the wall and the extremital 30 portion 11 of the clip 10 is made to engage in the socket formed by the struck-up portions 15, it is obvious that the base 1 will be supported from the wall in the manner illustrated in Fig. 3. If desired, the bracket 35 12 may be provided with a projection 16 embossed thereon and the extremital portion of the clip 10 may be provided with an opening 17 in which the projection 16 may engage when the parts are in the position 40 shown in Fig. 3. The inherent resiliency of the parts will cause the opening 17 to snap over the projection 16 to yieldingly retain the parts in the position shown in Fig. 3, and also yieldingly retain the bracket 12 on the 45 extremity of the clip 10 when the heater is first supplied to the user and before the bracket 12 is secured in place.

When it is desired to support the heater upon the wall, the heater proper is disconnected from the part 6, if it happens to be connected therewith, and is connected with the part 4 of the three-way connection, the part 6 then being closed by means of the closure cap 8. The position of the gas supply 55 conduit 7 is not changed, as it will serve to supply, when connected with the part 5, either the part 4 or the part 6 of the three-way connection. The base is then attached to the wall, as indicated in Fig. 3. If circumstances will permit, it is obvious that the base may first be applied to the wall before the heater is connected to the part 4.

From the foregoing, it will be seen that when the base is supported upon a horizontal surface, the heater is connected to the

vertical portion 6 of the three-way connection, and the horizontal portion 4 of such connection is temporarily closed. If it then be desired to support the base from the wall, the heater is removed from the vertical portion 6 of the three-way connection and the closure cap 8 is transferred from the part 4 to the part 6. The heater may then be connected with such part 4 of the three-way connection, and when the base is applied to 70 the wall, the heater will be supported in an upright position and the gas will be supplied thereto from the conduit 7. It will, therefore, be seen that the part 4 of the three-way connection serves as a vertically projecting part to which the heater may be connected when 75 the base is supported from a wall, and the part 6 of the three-way connection serves as a vertically projecting part to which the heater may be connected when 80 the base is supported in a horizontal position. The unchanged gas supply conduit 7 serves to supply gas to the heater through either of these parts depending upon which one is supporting the heater and which one 85 is temporarily closed by the closure cap 8.

It will now be noted that the above construction involves a very simple and effective means for rendering it possible to support the heater upon a horizontal surface or a 90 vertical surface, and that such means may be substantially constructed and does not involve the use of hinged joints which, of course, are objectionable in a gas heater of the present type.

Obviously numerous changes may be made in the details of construction without departing from the spirit or scope of the invention, as defined in the accompanying claims.

What I claim is:—

1. The combination with a gas heater, of a base provided with a three-way connection, one part of which serves as a means of connection for a gas supply conduit and either of the other two parts serving as a means of 110 connection for the heater, one of said two parts being adapted to removably support the heater in an upright position when the base is horizontally disposed and the other of said two parts being adapted to removably support the heater in an upright position 115 when the base is vertically disposed.

2. The combination with a gas heater, of a base provided with a three-way connection having interior gas passages, one part of 120 said three-way connection being adapted to be connected with a gas supply conduit and either of the other two parts serving as a means of connection for the heater, one of said two parts being adapted to removably support the heater in an upright position 125 when the base is horizontally disposed and the other of said two parts being adapted to removably support the heater in an upright position when the base is vertically disposed, 130

and means for closing the passage in that part of the three-way connection not being utilized for supporting the heater.

3. The combination with a gas heater, of 5 a base provided with a three-way connection having two parts that project horizontally and a third part that projects vertically when the base is horizontally disposed, one of such horizontally projecting parts serving 10 as a means of connection for a gas supply conduit and the remaining horizontally projecting part and the vertically projecting part serving as separate means of connection for the heater when the base is vertically disposed and horizontally disposed 15 respectively.

4. The combination with a gas heater, of a base adapted to be supported upon a horizontal surface, means whereby the base may be supported from a vertical surface, a multi-part connection associated with the base, one part of which is designed to removably support the heater in an upright position when the base is horizontally disposed and another part of which is designed to removably support the heater in an upright position when the base is vertically disposed, and means associated with said connection for supplying gas to the heater in either position of the base. 20 25 30

In testimony whereof I affix my signature.
TRUMAN G. PALMER.
